CLAIM

The ornamental design for a dual blade automotive windshield wiper, as shown and described.

DESCRIPTION

FIG. 1 is a perspective view of a dual blade automotive windshield wiper showing my new design with a mounting bar shown in broken lines for illustrative purposes forming no part of the claimed design;
FIG. 2 is a side elevation view thereof which is identical from either the left side or the right side;
FIG. 3 is a top plan view thereof;
FIG. 4 is an enlarged end elevation view from one end thereof;
FIG. 5 is an enlarged end elevation view from the other end thereof; and,
FIG. 6 is a bottom plan view thereof.

FIG. 1

FIG. 2

FIG. 3

FIG. 4

FIG. 5

FIG. 6
